UNITED STATES PATENT OFFICE.

GUNNARD A. OBERG, OF JAMESTOWN, NEW YORK, ASSIGNOR TO BLACKSTONE MANUFACTURING COMPANY, OF JAMESTOWN, NEW YORK, A CORPORATION OF NEW YORK.

CYLINDER FOR WASHING MACHINES.

Application filed November 15, 1922. Serial No. 601,199.

To all whom it may concern:

Be it known that I, GUNNARD A. OBERG, a citizen of the United States, residing at Jamestown, in the county of Chautauqua and State of New York, have invented certain new and useful Improvements in Cylinders for Washing Machines, of which the following is a specification, reference being had to the accompanying drawings, and to the reference characters marked thereon, which form a part of this specification.

This invention relates to metal cylinders and more particularly to that type of cylinders used in washing machines.

15 The principal object of the invention is to use a light sheet metal, such as aluminum, both for the body, the ends and the lid or closure for the aperture in the body; and to so brace the same as to hold the parts properly together to form a durable structure.

Another object of the invention is to so construct the adjacent edges or meeting parts of the metal by proper seaming or bending that soldering or other fastening 25 means will be unnecessary.

A further object of the invention is to so arrange and bend the sheet metal as to provide interior radial clothes-engaging ribs extending longitudinally of the body of the 30 cylinder,—the ribs and body portion being made of one piece of metal.

The invention consists in the devices and combination of devices illustrated, described and hereinafter set forth in the claims, and 35 will be more fully understood as I proceed with my specification.

In the drawings:

Fig. 1 is a vertical, transverse, sectional view of a cylinder constructed in accordance with my invention, looking toward the inside of one end of the cylinder.

Fig. 2 is a detail sectional view, enlarged, of a portion of the cylinder, the section being taken longitudinally of the cylinder in 45 the plane of the line 2—2 of Fig. 1.

Fig. 3 is a sectional view, on the same scale, of the parts shown in Fig. 2, the section being taken in the plane of the line 3—3 of Fig. 1.

50 Figs. 4 and 5 are sectional views, also enlarged, of the end wall and that portion of the body adjacent thereto, which defines the edge of the opening through the cylinder, both sections being taken in the plane

of the dotted line 4—4 of Fig. 1, the latter with the lid in the closed position.

Fig. 6 is a perspective view, enlarged, partly in section, looking at the inside of the cylinder, to show more clearly the parts hereinafter described.

Fig. 7 is a sectional view, enlarged, showing the manner of connecting the end wall with the body wall of the cylinder, the section being taken in the plane indicated by the dotted line 7—7 of Fig. 1.

Fig. 8 is a longitudinal, sectional view of the cylinder taken in the plane of the dotted line 8—8 of Fig. 9.

Fig. 9 is an elevation of one end of the cylinder.

Fig. 10 is a sectional view of a detail, taken on the plane of the dotted line 10—10 of Fig. 9.

In said drawings, A represents the cylinder as a whole, comprising a cylindrical body portion 1, having a suitable opening 2 therein, a sliding lid or cover 3, and two end walls 4. Each end margin of the body portion is bent upon itself, as shown more clearly in Fig. 5, to form the thickened edge 5. Each end wall 4 is circular or disc shaped, as shown in Fig. 1, and is provided with an outwardly extending annular flange 6 which is bent or seamed at 7 and then turned in as shown at 8, so as to cover and surround the thickened edge 5 of the body 1. It will be observed by reference to Fig. 5, that the flange 6 fits nicely upon the inside of the inner surface or wall of the body 1, while the extreme end 8 is pressed against the outside surface or wall of the body 1.

The body 1 is a piece of rectangularly shaped metal, bent into circular form so as to make substantially three-quarters of the circumference of the cylinder when completed; the other quarter being the opening 2 through the cylinder which is covered by the sliding lid 3.

At four diametrically opposite points the body 1 is bent inwardly and then outwardly to form a double longitudinal rib 9. Each rib 9 carries interiorly a bolt 10 which extends through the wall 4 and is suitably held by a nut 11 on the outside of the walls 4. Thus the body 1 and the two end walls 4, 4, are united and held together. The end walls 4, at the places where the edges

of the ribs 9 contact therewith, are indented or bent outwardly as shown at 12 (Fig. 3) to form seats for the edges of the ribs 9.

The metal on the return looped portion of 5 the two ribs 9 which are adjacent the opening 2, is bent upon itself as indicated at 13, to form a rounded or grooved margin 14, which two margins are parallel to each other and define the longitudinal walls of 10 the opening 2. The end or circumferential walls of said opening 2 are defined by the rounded edges 15 of two strips of metal 16, each strip being bent upon itself in the manner indicated in Figs. 4 and 6. The major 15 portion of each strip 16 is positioned between the parts 6 and 8 of the two end walls and is also embraced by a part of the body flange 5. It will thus be understood that the strip 16 is bent so that its circumferential line will be continuous with the circumference of the cylinder body as shown in Fig. 1, the bent portions 6, 8, of the end wall embracing the thickened portion 5 of the body and also the strip 16.

25 On the inside of each wall 4, the metal is bent or pressed outwardly to form the panels indicated at 17, and it follows from this that on the outside of the wall 4, these panels are separated by the flat surface of 30 the wall, thus forming a convenient space for a cast metal trunnion bracket 18, the three arms of which bracket are suitably secured to the wall 4, as by the rivets 19.

That portion of the metal forming the 35 two sides of one of the ribs 9 is spaced apart sufficiently to embrace and frictionally hold a strip 20, the projecting end of which extends outside of the cylinder and is bent about itself to form a bead 21. This bead 40 may hold a wire 22 if desired. The purpose of the bead 21 is to afford a stop for the sliding door 3 to limit its outward movement when the opening 2 is exposed. Each end portion of the lid is provided with an engaging flange formed by bending the metal over and then under, as clearly indicated at 45 23, whereby the lid has a bearing upon and will readily slide over the flanges 6, 8, of the end walls 4. The longitudinal margins 50 of the lid 3 are beaded as shown at 24, 25, by being bent over wires 26, 27, respectively. It will be understood that when the door is open, the beaded edge 24 will rest against the bead 21 of the body portion, the latter 55 acting as a stop to limit the movement of the lid; and that when the lid is swung to cover the opening 2, the beaded edge 25 will rest upon the bent over metal 13 so as to cover the margin 14 of the opening 2.

60 Usually a lock will be employed to hold the lid in closed position, but such being no part of the present invention, is not shown in the drawings.

I claim as my invention:

65 1. A cylinder of thin sheet metal comprising

ing a body member, a lid member and two end members, the body member being of perforated metal in tubular form of less than a complete cylinder and being bent upon itself to form thickened margins, the end members being provided with integral, outwardly extending, annular flanges adapted to embrace and hold the thickened margins of the ends of the body member, and a bearing flange on the lid member adapted to embrace the said annular flanges and permit sliding movement of the flanged lid thereover.

2. A cylinder of thin sheet metal comprising 80 a tubular body member, a lid member and two end members, the body member being of perforated metal and having its two ends stiffened by the metal being bent upon itself, an annular outwardly extending flange on each end member bent upon 85 itself to form an annular seat for and to clamp about the stiffened ends of the body member, the body and end members being further held together by bolts and nuts, and means for slidably mounting the lid upon 90 the end members.

3. A cylinder of thin sheet metal comprising 95 a tubular body member of perforated metal, bent to form less than the whole cylinder, two end members and a curved lid member, each of sheet metal, means for slidably mounting the lid member upon the end members, the metal of the body member being bent upon itself at its margins to form stiffened ends and smooth rounded 100 side margins, an annular flange integral with each end member bent upon itself to form a seat for and to embrace the stiffened end of the body member, the metal of the body member being further bent re-entrantly 105 to form a plurality of integral, radial ribs extending the full length of the cylinder body, one of said ribs being located adjacent each side margin of the body member, and locking bolts within the ribs extending 110 through the end members.

4. A cylinder of thin sheet metal comprising 115 two end members, a perforated body member and a lid member, each end member being provided with an annular flange adapted to seat and to embrace the end of the body member, a flange on the lid member providing a slidable engagement of the latter with the said annular flanges, and a shoulder on the body member against which the 120 lid member will abut to limit the sliding movement of the latter.

5. A cylinder of thin sheet metal comprising 125 two end members, a perforated body member and a lid member, each end member being provided with an annular flange adapted to seat and to embrace the end of the body member, a flange on the lid member providing a slidable engagement of the latter with the said annular flanges, and a shoul-

der on the body member against which the lid member will abut to limit the sliding movement of the latter, said shoulder comprising a beaded strip of metal clamped in a fold of the body member.

6. A cylinder of thin sheet metal comprising a perforated body member, two end members and a lid member, each end member having a flange shaped to form an annular recess, the body member being bent into cylindrical form, its ends seated in said recess and occupying less than the entire circumferential length thereof, so that the two proximate margins of the body member will define the sides of an opening in

the cylinder, a strip of metal located in each flange recess and extending from one body margin to the other to define the ends of the cylinder opening, and a bearing flange on the lid member providing a sliding engagement for the latter upon the end flanges.

In testimony that I claim the foregoing as my invention I affix my signature, in the presence of two witnesses, this 10th day of November, 1922.

GUNNARD A. OBERG.
